MACHINE COMPANY, A CORPORATION OF DELAWARE.

FIBER-BOARD CONTAINER.

1,211,873.

Specification of Letters Patent.

Patented Jan. 9, 1917.

Application filed March 21, 1916. Serial No. 85,542.

To all whom it may concern:

Be it known that I, JONATHAN PETERSON, a citizen of the United States, residing at Brooklyn, in the county of Kings and State 5 of New York, have invented new and useful Improvements in Fiber-Board Containers, of which the following is a specification.

This invention relates to certain novel and useful improvements in containers, and has 10 particular application to a container composed in whole or in part of box board, fiber board or similar substance.

In the preferred form of the invention shown herein, the container embraces a body 15 portion which is in the nature of a cylindrical wall of box board, fiber board or the like, having one end permanently closed by a cap which constitutes the bottom of the container while the opposite end of such body 20 portion is closed by means of a removable cap which forms a top or cover. In containers of this type the end caps are usually provided with circumferential flanges which fit over the ends of the cylindrical wall and 25 project beyond the outer face of the latter. In some instances both of the caps may be made of fiber board or the like, while in other cases one of the caps, for instance the bottom, or permanently attached cap, may 30 be composed of the box board or fiber board while the top, or removable cap, may be constructed of metal.

In the first mentioned class of containers, wherein both of the end caps are made of 35 fiber board, the outer peripheral faces of the flanges of such caps lie in a plane beyond the plane of the outer face of the cylindrical wall of the container. Under such circumstances, it is practically impossible to 40 smoothly and neatly apply an encircling band or label to the container, when it is desired to have the edges of the label encircle or overlap at least a portion of the end flanges of the caps, because of the gaps resulting by reason of the projecting ledges or shoulders formed by the end flanges. When an attempt is made to apply the label 45 the usual result is that such label is wrinkled, creased or distorted along and adjacent to the circumferential lines or ledges at the ends of the flanges of the caps. The ultimate result, therefore, is an unsightly appearing receptacle in so far as concerns its 50 external wrapper.

55 In the second mentioned class of contain-

ers, where the container embodies a permanently attached or bottom cap of fiber board and a removable or top cap of metal, the circumferential flange of the fiber board cap, owing to the nature of the material employed is usually thicker or of greater cross diameter than the circumferential flange of the metallic cap. The result is that the fiber board flange will not only project beyond the outer face of the cylindrical wall of the 60 container to a greater distance than the metallic flange but of course will also extend beyond the plane of the latter so that the two flanges will lie in different planes while both will extend beyond the outer face 65 of the cylindrical wall of the container. Consequently, in the operation of applying the usual printed adhesive label circumferentially of such a container it is impossible to affix the label smoothly and evenly 70 because of the tendency of the latter to assume an askew position on the container during the label applying operation, this being due primarily to the difference in circumference of the two cap flanges. Thus 75 when the two ends of the label are brought into overlapping relation, or when the two ends of the label meet, one side edge of the label will extend or project beyond the 80 adjacent end of the container. It is, therefore, the usual practice, when applying the label in the manner above mentioned, for the operator to first tuck in or fold over this 85 projecting edge, this tucking operation not only involving delay, but also detracts from 90 the appearance of the labeled receptacle. Furthermore, such uneven application of the label is accompanied by the appearance of 95 creases and wrinkles which further mar the appearance of the container. With my invention, however, I obviate these difficulties and disadvantages incident to the application 100 of the label to containers of the two types above recited. In the case where both of the caps are made of fiber board, I press the material at the ends of the cylindrical wall of the container to form inwardly offset necks, as hereinafter described, which necks are adapted to have the flanges of the 105 caps fit thereover, so that when both caps are applied the outer faces of the cap flanges will lie substantially flush with the outer face of the cylindrical wall of the container and the two flanges will lie in the same 110 plane.

In the case where one of the caps is made of fiber board and the other cap is made of metal, I so construct the container that the flanges of the two caps will, when applied, lie in substantially the same plane irrespective of the fact that the flange of one cap is of greater thickness than the flange of the other cap. Thus with both of the types of containers above mentioned, when made in accordance with my invention, the label, in the label applying operation, may be affixed smoothly, evenly, rapidly and conveniently with the two ends of the pasted label meeting with the side edges thereof in substantially true alinement so that the label will present a neat and attractive appearance. At the same time in the labeling a container of the type having a fiber board cap and a metallic cap the delay, and consequent expense, as well as the annoyance incident to tucking in or folding over one end of the label will be avoided. It is also my purpose to provide a container in which the removable cap or cover will fit snugly and securely in place so as to preserve the contents of the container against the deteriorating action of air when the contents are of such nature as to be unfavorably affected by the air. At the same time the cover may be quickly and readily removed when desired, the construction of the container being such as to render it capable of withstanding the wear and tear and rough usage to which the package is subjected in the repeated removal and application of the cover. Furthermore, in preparing an end of the fiber board cylindrical wall for the reception of the fiber cap, I make use of suitable instrumentalities, such as dies or the like, and circumferentially compress the material at the end of the wall so that an inwardly extending off-set ring-like neck results, which forms an annular shoulder at the inner face of the cylindrical wall as well as the outer face thereof. Furthermore, I propose to provide a container of this type which will embody the desired features of simplicity, convenience and efficiency, and which may be manufactured in quantities at a relatively low cost.

With the above recited objects and others of a similar nature in view, my invention consists in the construction, combination and arrangement of parts set forth in and falling within the scope of the appended claims.

In the accompanying drawings, Figure 1 is a perspective view of a labeled container embodying my invention; in this instance both of the end caps of the container being made of fibrous material. Fig. 2 is a vertical sectional view taken through a container such as is shown in Fig. 1. Fig. 3 is a vertical sectional view taken through the cylindrical wall or body portion of the

container, the end caps and label being omitted. Fig. 4 is a perspective view of a relatively short container having a bottom cap of fibrous material and a top cap of metal. Fig. 5 is a vertical sectional view taken through the container shown in Fig. 4. Fig. 6 is a vertical sectional view taken through the cylindrical wall, or body portion of the container, the top cap and label being omitted and the bottom end being shown adjacent the bottom end of the body portion and ready for application.

I will first describe my invention as embodied in the form of container shown in Figs. 1-3 inclusive, wherein both the end caps as well as the body portion of the container are composed of fiber board, box board, or other similar material. Referring now to said Figs. 1-3, the numeral 1 indicates the body portion of the container, which is in the nature of a substantially cylindrical wall and is preferably made up of fiber board, box board, or the like. In preparing the open ended cylindrical body portion, or wall, for the reception of the end caps, I subject the ends of such body portion to pressure, applied through the medium of suitable instrumentalities, or machinery, such as dies or the like, so that an upper inwardly off-set neck 2, and a lower inwardly off-set neck 3 will result. The pressure exerted by the dies in the formation of the necks results in solidifying or rendering more dense the material constituting the necks, and at the same time also results in the formation of the exterior circumferentially extending ledges or shoulders 4 and the interior annular ledges or shoulders 5. In this connection there is to be noted that the inwardly off-set necks 2 and 3 are formed by compressing the ends of the cylindrical wall, and without removing any material, as contradistinguished from rabbeting or cutting away the material to form the necks, and thus I not only avoid the weakening of the neck sections, which would result with the material cut away or removed but on the contrary, the compression of the fibrous material solidifies and strengthens the neck sections of the cylindrical wall. Furthermore, the neck sections 2 and 3 produced as above mentioned, are preferably of slightly tapered form, that is to say, are of less width at the outer or rim edges than at the shoulders 4 and 5, or the points where the necks merge into the body of the cylindrical wall. The bottom cap for the container is shown at 6, and is also preferably made of fibrous material, this cap having a flange 7 which is also preferably subjected to compression between suitable dies to give it a taper reverse to the taper of the neck 3 of the cylindrical wall; that is to say, the circumferential flange 7 is thicker at the bottom or

where it merges into the disk section of the cap than at its top edge, so that when the cap is applied to the container, as shown in Fig. 2, this tapered flange will fit snugly 5 against the reduced, compressed neck of the cylindrical wall and the outer face of the flange will be substantially flush with the outer face of the cylindrical wall. When the bottom cap is placed in position it may 10 be permanently attached to the cylindrical wall, preferably by means of an adhesive applied between the inner face of the cap thereof and the tapered neck of the cylindrical wall. In connection with the permanent 15 application for securing the bottom cap to the cylindrical wall, I wish to call attention to an important advantage resulting from the tapering of the inwardly off-set neck and the flange of the bottom cap 20 in reverse directions.

In the operation of applying the cap the flange is subjected to a certain degree of moisture, due partly to the adhesive and partly to the moisture resulting from the 25 steaming operation. Were the flange and neck of the cylindrical wall of uniform cross section throughout, in the application of the flange the flange would have a tendency to scrape or push the adhesive upward 30 on the neck of the shell so that it would ooze or flow out over the top edge of the cap flange thereby not only removing an amount of adhesive, which would be useful, and in some cases needful to properly 35 cure the cap, but would also detract from the appearance of the container. When the cap flange and neck are reversely beveled as shown, however, and the cap is applied as 40 illustrated in Fig. 2, the adhesive will, of course, not be pushed or forced upward and outward over the top edge of the cap flange, as any scraping action on the adhesive by the flange will be avoided. As the moisture 45 of the cap flange evaporates after the cap has been applied, this flange will, of course, contact to a certain extent, and have a tendency to tightly grip or bind against the neck. The removable cover, or top cap, is shown at 50 8 and is similar in construction to the bottom 55 cap, that is to say, the flange 9 is preferably slightly tapered or beveled downward toward its rim or free edge, or in other words, it is beveled reversely to the slight bevel of the neck 2 so that the cap will fit snugly over 60 the neck, yet may be easily removed therefrom. When this top cap is applied the outer 65 face of the flange 9 will also lie flush with the outer face of the cylindrical wall 1 and consequently will lie in the same plane with the outer face of the flange 7 of the bottom cap 6. Consequently an adhesive label, such as is shown at 10, may be applied neatly and smoothly to the container. These labels are usually of elongated form, and are applied so that the longitudinal axis of the

label extends circumferentially about the container. Now as I make the container shown in Figs. 1-3 inclusive, with the flanges of the caps flush with the cylindrical wall or body portion of the container, the 70 labels may be applied truly, evenly and smoothly, and the ends will meet squarely, while the edges of the label may, if desired, overlap the flanges of the caps. It will also be noted that with the container shown in 75 Figs. 1-3 inclusive, there are no exterior pronounced shoulders or ledges formed by the flanges of the caps when applied to the cylindrical wall, so that there is no tendency for creases or wrinkles to form in the label. 80

In the structure shown in Figs. 4-6 inclusive, I employ a bottom cap of fibrous material while the top, or removable cap is made of tin or other suitable metal. In this case while the lower end of the cylindrical wall is provided with the reduced, compressed tapered and inwardly off-set neck, such as is shown at 11, and which is similar to the necks 2 and 3 of the container shown in Fig. 1, it is not necessary that the outer 90 faces of the flanges of the two caps should lie flush with the outer face of the cylindrical wall. Referring to said Figs. 4-6, the numeral 12 indicates the fibrous cap having the flange 13 which is slightly tapered reversely to the flange 11, for the purpose before mentioned. The outer face of the flange 12 in this instance will project slightly beyond the face of the intermediate section 1' of the cylindrical wall, and at the 100 same time the outer face of this flange 13 will lie in substantially the same plane as the outer face of the flange 14 of the metallic cap 15, which constitutes the removable top or cover for the container. This cap 15 is adapted to removably fit the upper end of the cylindrical wall, the flange 14 being of suitable diameter to slip over the end of the cylindrical wall and yet to fit closely or neatly on the latter so as to protect the 110 contents of the container when the cap is applied. This cap 15, when made of metal, is very thin and hence the upper end of the shell need not be formed with the reduced neck as is desirable when a fibrous cap is employed. Owing to the nature of the materials, the flange 14 of the metallic cap is, of course, relatively thin when compared with the flange 13 of the bottom or fibrous cap, yet when both caps are applied they 115 will be of the same maximum cross diameter as is clearly shown on the dotted lines a in Fig. 5 of the drawings, and consequently the outer faces of both of these flanges will lie in the same plane. It will 120 be evident that this is due to the fact that the beveled flange 13 of the fibrous cap 12 fits over and meets the correspondingly chamfered or beveled neck 11 of the shell so that the flange 13 will not extend beyond 125 130

the flange 14 of the metallic cap even though it be thicker than the latter. This container, shown in Figs. 3-6 inclusive, is also intended to have a label such as is shown at 16 5 applied thereto. I have shown this form of container as made relatively short so that it is adapted as a receptacle for tobacco, snuff, or other products. By reason of applying the caps as herein set forth, that is 10 to say, so that the outer faces of the cap flanges are in the same plane, the ends of the label, when applied, will meet squarely and abut evenly as shown at 17, while there will be no projecting end or extension of one 15 end of the label to be tucked or folded in as is the case where the label is applied to the ordinary container of this type. The result is that the label may be applied, evenly, smoothly and neatly and will be devoid of 20 unsightly wrinkles or creases. This is because in the operation of applying the label, the maximum diameter of the two flanges being the same, the label will follow a true or straight path instead of tending to bear 25 off or work to one side which would cause the label to be applied askew.

I do not limit myself to the use of all the features of this invention together, but may employ the different novel features separately. It is also understood that the embodiment of the invention described herein is only one of the many embodiments or forms the invention may take, and I do not wish to be limited in the practice of the invention nor in my claims to the particular embodiment set forth.

What I claim is:

1. As a new article of manufacture, a container comprising a shell of compressible material having one end portion thereof compressed to produce an inwardly off-set neck, a cap having a flange fitting over the off-set neck of the shell and permanently secured thereto and a removable cap for the 40 opposite end of the shell, said removable cap having a flange of less thickness than the flange of the first-mentioned cap, the outer surfaces of both flanges lying in a perimeter of equal radius when the caps are 45 applied to the shell.

2. As a new article of manufacture, a container comprising a cylindrical shell of compressible material, having one end portion thereof compressed to produce an inwardly off-set tapered neck, a cap also of 50 compressible material having a tapered com-

pressed flange fitting over the neck of the shell and permanently secured thereto, said flange being tapered reversely to the taper of the neck of the shell, and a removable 60 cap for the opposite end of the shell having a flange of less thickness than the flange of the first mentioned cap, the outer surfaces of both cap flanges lying in a perimeter of equal radius when the caps are applied to the 65 ends of the shell.

3. As a new article of manufacture, a container comprising a cylindrical shell of fibrous material, one end of said shell being compressed to form an inwardly off-set neck, 70 a fibrous cap adapted to be permanently attached to said neck, and having a flange fitting said neck, and a removable metallic cap for the opposite end of the shell having a flange the outer surface of which lies in 75 a perimeter of the same radius as the perimeter of the flange of the fibrous cap when the caps are applied to the ends of the shell.

4. As a new article of manufacture, a container comprising a cylindrical shell of 80 fibrous material having heads with flanges closing the ends of said shell, at least one of said heads being of fibrous material, the said shell having the material at one end thereof compressed to provide a reduced neck adapted to receive the flange of one of said heads, 85 said flanges having their outer faces substantially in alinement with each other and with the outer face of said shell.

5. As a new article of manufacture, a container comprising a cylindrical shell of fibrous material having heads with flanges closing the ends thereof, at least one of said heads being of fibrous material, the said shell having the material at one end thereof 95 compressed to provide a neck of less thickness than the main body portion of the shell, said neck being adapted to receive the flange of one of said heads, the adjacent contacting walls of the said neck and flange respectively 100 being correspondingly inclined, the outer peripheral faces of the flanges at the opposite ends of the shell lying in substantially the plane of the outer peripheral surface of the body of the shell.

In testimony whereof I have hereunto set my hand in the presence of two subscribing witnesses.

JONATHAN PETERSON.
